UNITED STATES PATENT OFFICE.

DAVID RENSHAW, OF COHASSET, MASSACHUSETTS.

STEAM-BOILER.

SPECIFICATION forming part of Letters Patent No. 256,446, dated April 11, 1882.

Application filed April 29, 1881. (No model.)

To all whom it may concern:

Be it known that I, DAVID RENSHAW, a citizen of the United States, residing at Cohasset, in the county of Norfolk and State of Massachusetts, have invented certain new and useful Improvements in Steam-Boilers, of which the following is a specification.

My invention is specially an improvement upon marine boilers, and by it I gain an economy of space with an economy of fuel over the boilers at present known to me; and it is more particularly designed as an improvement upon the patent granted to D. Renshaw and G. B. N. Tower, December 18, 1877, No. 198,213.

In the drawings I have shown in Figure 1 a cross-section of my boiler in two parts, the one marked Y representing the furnace portion of the boiler and that marked X the flue portion. In Fig. 2 I show a partial elevation with a portion of the shell removed, and partial section (longitudinal) of the part marked Y and a longitudinal section of the part marked X.

A represents the outer shell of my boiler, within which are inner shells B, inclosing furnaces, and inner shells C, inclosing flues. The shells B surround furnaces and contain within them the grate D and the bridge-walls E, the bridge-walls being near the rear of the furnace-chambers in the part Y. a a are water-tubes, which extend from the outer sides of the shells B through the furnace-chambers to the crown of the furnace, taking the water from the sides of the boiler to the tops of the furnace-chambers. The furnace-chambers are separated by a water-leg, b, running the whole length of the part Y. From this construction it ensues that a thorough circulation is established throughout this portion of the boiler.

After the heated gases pass the bridge-walls they enter the flues C, said flues being separated by a water-leg, c. On the sides of these water-legs water-tubes d, bent to nearly a semi-circular form, are fitted in series, as shown, so

as to fill a large portion of the flues C and retard the passage of the gases between them, 45 thus imparting their heat to the water, and the water-leg c is made much larger than the water-leg b for the reason that the circulation through tubes d commences and ends in said water-leg. Therefore it is requisite that the 50 body of water in the leg should be of sufficient capacity to supply the currents of water rising through the tubes d. Near the end of the part X the flues emerge into an open space or uptake, G, from which the gases are conducted 55 in any convenient manner. I have shown them as passing from this uptake through a horizontal flue, e, to a chimney, H, said chimney being surrounded by a steam drum or jacket, J.

It will be seen that by this improvement I 60 give a very large amount of heating-surface, both shell-surface and tubular, to the action of the fire and its resultant gases, thus securing the desired economy of space, and delay the progress of the gases through the boiler in 65 such a manner as to take from them the greater portion of their heat, thus securing the desired economy of fuel.

There may be cases in which I should prefer to use the part Y separately from the part X, 70 or to use the part X with a furnace of different construction, in either case producing good results; but I prefer to use them together, as shown.

I claim as my invention—

A boiler having outer shells, A, and inner shells, C, said inner shells inclosing a furnace and flues, and said flues containing within them bent water-tubes d, emerging from and entering a central water-body, c, substantially 80 as described.

DAVID RENSHAW.
